UNITED STATES PATENT OFFICE.

JOHN J. TOWNSEND, OF PORTSMOUTH, VIRGINIA.

DESIGN FOR A COMPASS-CARD.

SPECIFICATION forming part of Design No. 22,723, dated August 22, 1893.

Application filed July 22, 1893. Serial No. 481,229. Term of patent 14 years.

To all whom it may concern:

Be it known that I, JOHN J. TOWNSEND, of the city of Portsmouth, county of Norfolk, and State of Virginia, have invented a certain new and original Design for a Compass-Card, of which the following is a full, clear, and exact description.

My design for a compass card is fully shown in the accompanying drawing and comprises a circular chart having a series of radiating marks corresponding to the points of the compass and at the cardinal points having the usual symbols arranged as shown. From the north point, near the edge of the card, ex-

tends a spirally disposed line terminating on 15 radial line with the starting point of the line, between the starting point and the center.

Having thus described my invention, what I claim, and desire to secure by Letters Patent, is—

20 The design for a compass card substantially as shown and described.

In witness whereof I have hereunto set my hand this 19th day of April, A. D. 1893.

JOHN J. TOWNSEND.
